UNITED STATES PATENT OFFICE.

WILLIAM BRIGGS, OF BROOKLYN, NEW YORK; MAGDALENA M. BRIGGS EXECUTRIX
OF SAID WILLIAM BRIGGS, DECEASED.

FLUSH-TANK.

1,149,494.

Specification of Letters Patent. Patented Aug. 10, 1915.

Application filed January 21, 1915. Serial No. 3,425.

To all whom it may concern:

Be it known that I, WILLIAM BRIGGS, a citizen of the United States, and residing at Brooklyn, in the county of Kings and State of New York, have invented certain new and useful Improvements in Flush-Tanks, of which the following is a specification, such as will enable those skilled in the art to which it appertains to make and use the same.

This invention relates to flush tanks for use in waterclosets and like places, and particularly to the valve construction for discharging the water from said tanks, and the object of the invention is to provide an improved valve construction whereby the valve and valve seat may be quickly and easily cleaned or repaired whenever necessary without loosening the connection of the discharge pipe in the bottom of the tank, or producing leakage at this point; and with this and other objects in view the invention consists of the construction, combination and arrangement of parts hereinafter described and claimed.

The invention is fully disclosed in the following specification, of which the accompanying drawing forms a part, in which the separate parts of my improvement are designated by suitable reference characters in each of the views, and in which:—

Figure 1 is a side view of a flush tank provided with my improvement, part of the tank being broken away and part of the construction being shown in section; Fig. 2 a sectional view of the water discharge mechanism detached from the tank; Fig. 3 a view similar to Fig. 1 but showing the parts in a different position; and, Fig. 4 a plan view of a spider cap which I employ and which is shown in full lines in Fig. 1 and in section in Figs. 2 and 3.

In the drawing forming part of this specification, I have shown at *a* an ordinary flush tank having a bottom *a*² in which is secured a discharge pipe *b*.

The discharge tube *b* is threaded at its lower end as shown at *b*² and is passed downwardly through the bottom of the tank and is provided with a washer *b*³ below which is placed a nut *b*⁴ and a pipe *c* is con-

nected with the tube *b* by means of a coupling nut *c*², and the pipe *c* leads to the basin, not shown, in the usual manner.

The upper or inner end of the tube *b* is provided with a cage *d* formed integrally with said tube, and comprising a bottom circular member *d*² and a top annular member or band *d*³ connected with the bottom circular member *d*² by vertical rods or bars *d*⁴.

I also provide a spider cap *e* which is shown in full lines in Fig. 1, in section in Figs. 2 and 3, and a plan view of which is given in Fig. 4, and this spider cap involves a rim or band member *e*² adapted to receive the annular top member *d*³ of the cage *d*, and the spider cap may be detachably secured to said part *d*³ by a set screw or screws *f*, or by means of a screw-thread or in any other way.

The spider cap *e* is provided with a central circular opening *e*³ through which is loosely passed and through which is movable, a valve tube *g* provided at its lower end with a valve *g*² adapted to be seated on and to closely fit an annular valve seat *b*⁶ in the top of the tube *b*.

The valve tube *g* is provided at the top thereof with a spider cap *h* having a central vertical screw-threaded shank *h*² provided with an aperture *h*³, and I also employ, in the construction shown, a hollow cone device *i* which is passed down over the valve tube *g* and through the top of which the threaded shank *h*² of the spider cap *h* passes, and said cone device is secured on the valve tube *g* by a nut *j* and washer *j*².

The valve tube *g* is vertically movable and may be raised in the usual or any desired manner by means of a lever or other device connected with the threaded shank *h*² by a wire or similar device *j*². The lever or other device for raising the valve tube *g* is not shown for the reason that they form no part of this invention and any suitable means may be provided for this purpose.

In the operation of this construction the flush water normally, or under normal conditions, passes through the cage *d* and through the tube *b* when the valve *g* is raised, but if at any time the water *h* should rise too high in the tank *a*, it will

flow through the siphon members *i* and *g* and discharge through the tube *b* and pipe *c*; as will be readily understood, and it is in order to accomplish this result that the 5 valve support *g* is made in the form of a tube, and a supplemental siphon attachment applied thereto.

Heretofore in devices of this class the cage *d* has been detachably connected with 10 the tube *b* by means of a screw-thread and the spider cap *e* or a similar device has been formed integrally with the cage *d*, and in order to repair the valve *g*², or the valve seat *b*⁶, it was necessary to detach said cage 15 from the tube *b* and this frequently resulted in loosening the tube *b* in the bottom of the tank *a* and causing a leak at this point, or around said tube. With my improvement, however, all that is necessary is to detach 20 the spider cap *e*, and said cap and the valve tube *g* and the part *i* connected therewith may be removed or detached, and said valve seat and valve may be cleaned or repaired, after which the said valve tube with the 25 spider cap *e* may be again connected with the cage *d*.

The circular bottom member *d*² of the cage *d* which is formed integrally with the tube *b* projects beyond said tube and a packing washer *m* is placed between the same and this together with the washer *b*³ and nut *b*⁴ insures a watertight connection between said tube and the bottom *a*² of the tank.

5 The great advantage of this construction will be apparent to all those familiar with this class of devices, and my invention is not limited to the use of the cone device *i* and any other suitable means may be used 10 in connection with the valve tube *g* for forming a siphon, and changes in and modifications of the construction herein described may be made, within the scope of the appended claims, without departing from the

spirit of my invention, or sacrificing its advantages. 45

Having fully described my invention, what I claim as new and desire to secure by Letters Patent, is:—

1. In a discharge mechanism for flush 50 tanks, a tube adapted to be secured in the bottom of the tank and provided in its inner end with a valve seat and an integral valve cage, a cap detachably connected with the top of said cage and a valve tube passing centrally through said cap and movable therethrough and provided at its lower end with a valve which operates in connection with said valve seat. 55

2. In a discharge mechanism for flush 60 tanks, a tube adapted to be secured in the bottom of the tank and provided in the top thereof with a valve seat, said top of the tube being also provided with a valve cage having a detachable cap member, a vertically 65 movable valve support passing loosely through said cap member and provided at its lower end with a valve which operates in connection with said valve seat.

3. In a discharge mechanism for flush 70 tanks, a tube adapted to be secured in the bottom of the tank and in a vertical position and provided in the top thereof with a valve seat inclosed by a cage having a detachable cap member, and a valve support 75 movable vertically through said cap member and provided at its lower end with a valve which operates in connection with said valve seat.

In testimony that I claim the foregoing 80 as my invention I have signed my name in presence of the subscribing witnesses this 19th day of January, 1915.

WILLIAM BRIGGS.
